CLAIM

The ornamental design for a weight measurement device, as shown and described.

DESCRIPTION

FIG. 1 is a perspective view of a weight measurement device showing our new design;

FIG. 2 is a front elevation view thereof;

FIG. 3 is a rear elevation view thereof;

FIG. 4 is a left side elevation view thereof, the right side being a mirror image thereof;

FIG. 5 is a top plan view thereof; and,

FIG. 6 is a bottom plan view thereof.

Broken lines shown immediately adjacent shaded areas represent bounds of the claimed design and unclaimed features. All other broken lines are directed to unclaimed features. The broken lines form no part of the claimed design.

1 Claim, 4 Drawing Sheets
